UNITED STATES PATENT OFFICE.

LLOYD S. MORROW, OF MONESSEN, PENNSYLVANIA.

SWITCH.

SPECIFICATION forming part of Letters Patent No. 784,341, dated March 7, 1905.

Application filed July 16, 1904. Serial No. 216,768.

To all whom it may concern:

Be it known that I, LLOYD S. MORROW, a citizen of the United States of America, residing at Monessen, in the county of Westmoreland and State of Pennsylvania, have invented certain new and useful Improvements in Switches, of which the following is a specification, reference being had therein to the accompanying drawings.

10 This invention has relation to switch-throwing devices, and more particularly to that class which are employed upon electric railways; and the object of this invention is to provide a device of this character which may be operated by the motorman of a car without the motorman leaving said car.

Another object of my invention is to construct a switch-throwing device which will be extremely simple in construction, strong and durable, and highly efficient in operation, the construction of the switch will be servicable, and it will be impossible for the same to be affected by the conditions which may surround the same.

25 It is a well-known fact that the switch-throwing devices which are now commonly employed upon electric railways are many of them operated by electrically-actuated appliances and are often rendered useless by water and the electrical circuits which surround the same, and in providing my improved switch-throwing device I have endeavored to overcome the many disadvantages of such devices heretofore used and construct a device which 30 will be manually operated.

Briefly described, my improved switch-throwing device consists of locating a casing in the road-bed of the railway adjacent to the switch-tongue, and I have provided novel 40 mechanism within the casing which when operated will throw the switch-tongue in any desired direction, and upon the car I construct a device which the motorman can operate to throw the switch-tongue without leaving the car. In the casing is provided a plurality of levers which are so connected to the switch-tongue as to throw the same in one or the other direction, these levers being operated by a rod which is adapted to be depressed by 45 the motorman to engage the mechanism car-

ried within the casing to throw the switch-tongue.

All of the above construction will be hereinafter described in detail.

Referring to the drawings accompanying 55 this application, Figure 1 is a top plan view of the casing containing my novel mechanism, showing the same located in the road-bed of a railway adjacent to the switch-tongue. Fig. 2 is a similar view with the lid of the casing removed. Fig. 3 is a longitudinal sectional view of the casing. Fig. 4 is an end view of the casing, showing the relative position of a car over the same, said car carrying the operating mechanism; and Fig. 5 is a side elevation of a portion of the casing, showing a car about to pass over the same.

Throughout the several views of the drawings like numerals of reference indicate like parts.

The reference-numerals 1 and 2 indicate the main rails of a track and 3 and 4 the rails of a siding which enters the main track, and the reference-numeral 5 indicates a switch-tongue which controls the movement of the car over 75 the main track and the siding, and to operate this switch-tongue I employ a casing 6, which is mounted within the road-bed between the tracks 1 and 2 and adjacent to the switch-tongue. The casing is preferably oblong in 80 shape and is provided with a lid 7, which may be secured upon the same by any desired means. The one side of said casing is provided with an opening 8, through which a rod 9 protrudes and is connected to the switch-tongue 5. The bottom 10 of the casing is cut 85 away at its one end to form a recess 11 horizontally within the casing, and formed in the bottom of the casing are the longitudinal recesses 12 and 14.

The reference-numerals 15 and 16 indicate two bell-crank, which are pivotally mounted, as indicated at 17 17, upon the bottom of the casing, the one end of each bell-crank being connected, as indicated at 18 18, to the rod 9, 95 while to the other end of the bell-crank are pivotally connected, as indicated at 19, rods 20 21, these rods being mounted within the longitudinal recesses 12 and 14 and having their outer ends pivotally connected, as indi- 100

cated by the reference-numeral 22, to upwardly-extending levers 23 24, these levers being mounted upon a pin 25, journaled in the bearings 26 26 26, mounted upon each side of the recesses 12 and 14. The upper ends of these levers are beveled, as indicated at 27, and they protrude through slots 28 29, formed in the lid 7 of the casing.

The reference-numeral 30 indicates guard-blocks, which are mounted upon the lid at each side of the slots.

The operating mechanism of the construction just described consists of rods 31 32, which are mounted vertically within a yoke 33, this yoke being secured under the platform 34 of a car, and the rods 31 32 pass through openings 35, formed in the platform, and have secured on their upper ends tread-blocks 36 36, and interposed between the tread-block and the yoke are spiral springs 37 37, which surround the rod 31 and normally hold the tread-block in its raised position:

The manner of operating my improved switch-throwing device to throw the tongue of the switch in either direction is as follows: Should the motorman desire to throw the switch-tongue in an opposite direction from that shown in the accompanying drawings—namely, to continue on the main track—the motorman would depress with his foot the tread-block 36, which would force the rod 31 downwardly, and upon the car passing over the forward end of the casing 6 the lower end of the rod 31 would strike the beveled end 27 of the lever 23 and move the same sufficiently to throw the rod 21 forward and throw the lever 9 through the medium of the bell-crank 16, whereby the switch-tongue would be moved away from the main rail to permit the passage of the car. Should it be desired to pass onto the siding when the switch-tongue is in an open position, the motorman depresses the other tread-block, which forces down the rod 32, and it will strike the lever 24 and through the medium of the rod 20 and bell-crank 15 the lever 9 will be operated to close the switch-tongue. It will be observed from the connections of the levers that when the lever 23 is operated the lever 24, rod 20, and bell-crank 15 will be moved to the reverse position to what it assumed before the lever 23 was engaged by the rod 31, this movement being true of the lever 21 and bell-crank 16 when the rod 32 strikes the lever 24.

By the novel form of construction shown and described it will be seen that it will be impossible for electric circuits or water to affect the general operation of the device, and while I have herein shown a preferred form of arranging the levers and operating the mechanism within the casing I do not care to limit myself to this special construction, but may vary the same, as will be permissible by the appended claims.

What I claim is—

1. The combination with a switch-tongue and a casing located adjacent to said tongue, the bottom of said casing being formed with a transverse recess and longitudinal recesses 70 communicating with said transverse recess, of a rod located in said transverse recess, said rod projecting through the side of the casing and being connected to the switch-tongue, two bell-crank levers pivoted in said transverse recess and pivoted to said rod, the opposite ends of the bell-crank levers extending inwardly toward one another, rods connected to the inwardly-extending ends of the bell-crank levers and extending through the longitudinal recesses, pivoted levers connected to said rods and extending through the top of the casing, spring-retracted tread-blocks carried by a car and rods carried by said tread-blocks and adapted to contact with said pivoted levers.

2. The combination with a switch-tongue of a casing located adjacent thereto, a horizontally-movable rod projecting through the side of the casing, and connected to the switch-tongue, bell-crank levers arranged within the casing, said bell-crank levers having each one end attached to said rod and the other ends of said levers projecting in opposite directions one to the other, rods connected to the oppositely-projecting ends of the bell-crank levers, vertically-disposed levers pivoted in the casing and attached to said rods and projecting through the top of the casing, and vertically-movable rods mounted on a car and adapted each to contact with one of said levers to move the switch-tongue in one or the other direction.

In testimony whereof I affix my signature in the presence of two witnesses.

LLOYD S. MORROW.
